UNITED STATES PATENT OFFICE.

WILLIAM R. HILDEBRAND, OF CHICAGO, ILLINOIS.

METAL-PROTECTED RUBBER HEEL.

1,307,737.

Specification of Letters Patent. Patented June 24, 1919.

Application filed September 5, 1916. Serial No. 118,313.

To all whom it may concern:

Be it known that I, WILLIAM R. HILDEBRAND, a citizen of the United States, residing at Chicago, in the county of Cook and State of Illinois, have invented certain new and useful Improvements in Metal-Protected Rubber Heels, of which the following is a specification.

My invention relates to rubber heels and its object is to metal-line the outer ends of the holes provided in this type of heel to be engaged by the screws or nails by means of which they are secured to the leather heel of the shoe. Another object is to metal-line the walls of the countersinks of these bores which are provided for the head of the nail or screw, so as to resist wear upon the rubber and prolong the life of the heel without the use of separate studs or plates which add to the weight, and interfere with the resiliency of the heel.

With these general objects in view my invention consists in the novel construction, combination and arrangement of parts, all as hereinafter described in detail, illustrated in the accompanying drawing and more particularly pointed in the appended claims.

In the drawing—

Figure 1 is a vertical section through the heel portion of a shoe provided with the present improvement.

Fig. 2 is a plan view of the bottom of the heel.

Fig. 3 is a broken away portion of Fig. 1 on an enlarged scale.

Fig. 4 is a vertical section of the rubber heel partly compressed by the weight of the wearer, and a section of the leather portion of the heel, showing freedom of movement in one of the fastening screws or nails.

Fig. 5 is a perspective view of one form of metal lining.

Fig. 6 is a modification of Fig. 5 and showing the metal bore lining and the usual embedded washer partly disconnected and flexibly connected.

Fig. 7 is a view of the blank out of which the Fig. 6 modification is formed.

In the several views 2 represents a fragment of a shoe with a leather heel section and a rubber heel section—3 and 4, respectively. The rubber heel 4 is shown provided with the usual screw or nail holes 5, in the present illustration six in number. The outer ends of the holes 5 are enlarged to

form counterbores 6 for metal linings engaged by heads 7 of screws or nails 8. Each counterbore 6 has its walls and bottom lined with a cylindrical steel shell having a bottom labeled 9 in Figs. 1 to 5 and 14 in Fig. 6, which functions as the usual embedded rubber heel washer which prevents the head from pulling through the bore 5. In Figs. 1 to 5 the lining has a tapered wall 10 on which is an edge flange 11, and in Fig. 6 a uniformly cylindrical wall 15 with a flange 18. The flanges provide metal contacts that resist wear upon the rubber without materially interfering with its resilience. When the flange is worn away the edge of the cylindrical wall will continue to function as a metal guard until the rubber is worn down to the bottom or washer portion 9 or 14.

The lining is made sufficiently large to permit the lateral movement of the head 7 indicated in Fig. 4. The bottom or washer portion 9 is provided with a nail or screw hole 12 and the bottom 14 with a hole 19 the indicated angular movement when the rear part of the rubber heel is compressed, as in walking, more than the forward part of said heel. The wall 10 is slightly divergent or enlarged inwardly to prevent its accidentally falling out, the metal lining being molded into the body of the rubber. An opening or space 13 is provided between the bottom portions which partly separates them from the tapered body 10, Figs. 1 to 5 and from the body 15 of Fig. 6. This permits liquid or plastic rubber to flow in between the edge 16 of the linings and the bottom or washer portion. The latter is elastically held to the wall portion 10 or 15 by a connective portion 17 which makes the washer portion partly independent of the cylindrical wall portion, at least to the extent of permitting a moderate degree of relative movement or flexibility.

As the conventional rubber heel must have a certain number of holes 5 for fastening screws or nails, lining these holes with metal in the manner indicated obviates many of the objections to studdings of metal and heel plates, and provides a neat means of metal-shoeing as indicated by a glance at Fig. 2, which to all appearances is the same as the plain rubber heel. In fact the rim of metal which lines the outer ends of the holes rather enhances than detracts from the appearance

on the selling counter by the metal lined holes not being ragged as is often the case with the ordinary nail holes.

Having thus described my invention, I
5 claim as new and desire to secure by Letters
Patent—

1. The combination with a rubber heel
disk having a nail hole therein, of a cylindri-
cal member closed at one end by a flexibly
10 connected washer to be engaged by a screw
or nail.

2. The combination with a rubber heel
having countersunk holes therein, of hollow
metal members lining the bottoms and sides
of the countersinks, washers to be engaged
by nails and the like, a connective portion 17
that flexibly connects each of said washers
with said members and protective metal
rings for the sides of the countersinks.

In testimony whereof I have hereunto
signed my name.

WILLIAM R. HILDEBRAND.
